DESIGN FOR A CLOCK

Willard G. Houston, Wadsworth, Ohio

Application April 22, 1940, Serial No. 91,865

Term of patent 3½ years

To all whom it may concern:

Be it known that I, Willard G. Houston, a citizen of the United States, residing at Wadsworth, in the county of Medina and State of Ohio, have invented a new, original, and ornamental Design for a Clock, of which the following is a specification, reference being had to the accompanying drawing, forming part thereof.

Figure 1 is a front elevation of a clock embodying the new design.

Figure 2 is a top plan view thereof.

Figure 3 is a side elevation thereof.

I claim:

The ornamental design for a clock, as shown.

WILLARD G. HOUSTON.
